By his Attorney

UNITED STATES PATENT OFFICE.

CHARLES A. DEARBORN, OF NEW YORK, N. Y.

DESIGN FOR A SEWING-MACHINE PRESSER-FOOT.

59,461.

Specification for Design.

Patented Oct. 25, 1921.

Application filed March 1, 1921. Serial No. 448,853. Term of patent 14 years.

To all whom it may concern:

Be it known that I, CHARLES A. DEARBORN, a citizen of the United States, and a resident of New York, county and State of New York, have invented a new, original, and ornamental Design for a Sewing-Machine Presser-Foot, of which the following is a specification, reference being had to the accompanying drawing, forming part thereof.

In said drawing:

Figure 1 is a front, perspective view of the new design for presser foot for sewing machines.

Fig. 2 is a top plan view of the same.

I claim:—

The ornamental design of a sewing machine presser foot, as shown.

CHAS. A. DEARBORN.
